UNITED STATES PATENT OFFICE.

ELMER L. DISNEY, OF GARBER, OKLAHOMA.

WARDROBE SUITCASE.

Application filed January 11, 1923. Serial No. 612,074.

This invention relates to a wardrobe suitcase and has for its principal object to provide a device whereby a suitcase frame may be employed for holding a plurality of drawers whereby various articles and wearing apparel may be more easily and neatly held in place within the suitcase whenever so desired.

Another important object of the invention is to provide a wardrobe suitcase of the above mentioned character, which enables the same to accommodate quite a large number of various articles of wearing apparel and the same will be so placed within the wardrobe suitcase as to be held in the proper position and in a neat manner whereby the person may have ready access to the same.

A still further object of the invention is to provide a wardrobe suitcase of the above mentioned character, which is simple in construction, inexpensive, strong and durable and further well adapted for the purpose for which it is designated.

A still further object of the invention is to provide a wardrobe suitcase of the above mentioned character, which is designed more specially for use while traveling and where it is desired to have a sufficient quantity of wearing apparel and accessories completely and compactly arranged to render the same readily accessible and without the usual inconvenience experienced in the use of the ordinary type of suitcase.

Other objects and advantages of this invention will become apparent during the course of the following description.

In the accompanying drawings forming a part of this specification and in which like numerals designate like parts throughout the same:—

Figure 1 is a perspective view of my wardrobe suitcase showing the arrangement of the various drawers within the suitcase.

Figure 2 is a central vertical section of the same, taken on the line 2—2 of Fig. 1.

Figure 3 is a transverse section taken on lines 3—3 of Fig. 2.

Figure 4 is a detail horizontal section showing the cover closed.

Figure 5 is a detail vertical, transverse section illustrating the same.

In the drawings wherein for the purpose of illustration is shown the preferred embodiment of my invention, the numeral 1 designates the body or receptacle of my wardrobe suitcase and is provided with the usual stationary back 2, end pieces 3 and 4 and the bottom 5. The front face of the receptacle is open as more clearly shown in Fig. 1 of the drawing.

So far the description of the above construction is to be found in the suitcases of the usual type now on the market. A plurality of spaced transverse strips or partitions 6 and 7 respectively are arranged and carried on the inner sides of the end pieces 3 and 4 of the receptacle 1 in the manner as more clearly shown in Fig. 2 of the drawing. These partitions or strips 6 and 7 extend across the full width of the end pieces 3 and 4 and adapted to be slidably mounted thereon are a plurality of longitudinally extending drawers 8. These drawers 8 extend across the full length of the interior of the receptacle 1 and are superposed with relation to each other as more clearly shown in Fig. 1 of the drawings.

The uppermost partitions or strips 6 and 7 which are carried by the inner sides of the end pieces 3 and 4 support a longitudinally extending partition 9 and this longitudinally extending partition 9 is provided with a plurality of spaced vertical partitions 10. A plurality of drawers 11 are adapted to be supported upon the partition 9 and between the vertical partition 10 formed thereon and these drawers 11 will then be in transverse relation with respect to the longitudinally extending drawers 8 which are slidably mounted upon the end strips 6 and 7 respectively. The longitudinally extending drawers 8 are for the purpose of holding the larger pieces of wearing apparel such as shirts, trousers,

coats and the like while the transverse drawers 11 are adapted to hold the smaller articles of wearing apparel such as collars, handkerchiefs and other accessories which 5 are used.

These drawers 8 and 11 are adapted to be withdrawn from the receptacle 1 for the purpose of permitting access to the same and the longitudinally extending drawers 10 8 are provided with handles 12 which are carried in the front faces of the drawers 8 intermediate its ends and these handles 12 are arranged in vertical alinement as more clearly shown in Fig. 1 of the drawings. 15 The transverse drawers 11 are provided with notches or grooves 13 formed therein in the front face for the purpose of permitting the person to place his fingers therein in order that the drawers 11 may be withdrawn from 20 the receptacle 1 whenever the case necessitates.

The receptacle 1 is provided with a hinged cover 14 which is hinged to the bottom 5 as more clearly shown at 15 in the drawings. 25 The hinged cover 14 is adapted to close the entire front open face of the receptacle 1 and will furthermore prevent the accidental displacement or withdrawal of the drawers 8 and 11 respectively from the receptacle 1 30 when in a closed position. The cover 14 is adapted to carry therein a pair of spaced supporting strips 16 and 17 respectively and these supporting strips 16 and 17 are placed within the cover 14 so that their inner ends 35 will be spaced from each other and so arranged that the space formed therebetween as shown at 18 in the drawings will be in vertical alinement with the handles 12 provided upon the longitudinally extending 40 drawers 8 for the purpose to be hereinafter more fully described. These supporting strips 16 and 17 which are carried in the cover 14 may be fastened thereto by any suitable fastening means and I do not wish 45 to confine myself to the manner in which the same are secured thereto. The supporting strips furthermore are provided with straps 19 and 20 and buckles 21 and 22 respectively for the purpose of permitting the supporting strips 16 and 17 to further hold additional pieces of wearing apparel when there 50 is no more room in the various drawers to hold the same.

When the hinged cover is in an open position; that is to say, the front face of the receptacle 1 is open so that the drawers 8 and 11 may be withdrawn therefrom, access can be had to the drawers 8 and 11 and when it is desired to close the receptacle 1 the hinged cover is swung upwardly and engages the ends 3 and 4 and the top of the receptacle in such a manner that the transversely extending face or slot formed between the supporting strips 16 and 17 will 60 communicate with the handles 12 formed or

carried on the receptacle 8 and thereby permit the cover to tightly fit over the open face of the receptacle and prevent the accidental withdrawal or sliding of the various drawers within the receptacle 1. The 70 hinged cover 14 and the top of the receptacle 1 may be further held in a closed position by providing suitable fastening means 23 as is customarily used on the suitcases of the type now in use and also suitable straps 75 provided with buckles at their respective ends may be passed through various loops carried by the suitcase 1 and the hinged cover 14 for further preventing the accidental opening of the hinged cover when 80 the suitcase is in a closed position.

The wardrobe suitcase as above described may be formed of any suitable material and in the present instance I have employed pressed cardboard or the like and I do not 85 wish to limit myself to the material used in conjunction with my wardrobe suitcase as any other material may be substituted therefor.

It will further be noted from the foregoing description that a wardrobe suitcase has been provided wherein a person who is constantly traveling will greatly appreciate the efficiency and time saved in using a wardrobe suitcase of the above mentioned 90 character. In the first place the various articles of apparel are kept in proper condition and further more it is not necessary to spend considerable time in looking through the contents of the suitcase in order to find 95 the desired article the person wants. The articles of apparel will at all times be kept in a compact and proper condition and the same are readily obtained by the person whenever so desired with the least possible 100 time and labor.

From the foregoing description of the construction of my improved apparatus, it will be seen that I have provided a simple, inexpensive and efficient means for carrying 105 out the objects of the invention, and while I have particularly described the elements best adapted to perform the functions set forth, it is obvious that various changes in form, proportion and in the minor details 110 of construction may be resorted to without departing from the spirit or sacrificing any of the principles of the invention.

What I claim as new and desire to secure 115 by Letters Patent is:—

A wardrobe suitcase comprising a casing, spaced partitions located therein and dividing the same into compartments, drawers 120 slidably mounted in the compartments and provided at their outer sides with knobs arranged in a row and which projects beyond the plane in which the edges of the casing lie when the drawers are in closed position 125 in the compartments, a cover having a continuous edge flange hinged at one side to the 130

casing at the outer side surface thereof and adapted to receive the edge portion of the casing, reenforcing strips mounted upon the inner side of the cover and spaced from each other at their inner opposite edges, the space between the edges of the strips adapted to receive the knobs when the cover is closed with relation to the body of the casing and securing straps mounted upon the strips and

adapted to bear against the outer faces of the sides of the drawers when the cover is closed over the casing and extending along lines at the opposite side edges of the space between the strips and the row of knobs and serving as buffers to prevent the knobs from having contact with the cover.

In testimony whereof I affix my signature.
ELMER L. DISNEY.
